Primary Examiner — Patricia A Palasik(74) *Attorney, Agent, or Firm* — Fish & Richardson P.C.(57) **CLAIM**

The ornamental design for a machine tool display panel, substantially as shown and described.

DESCRIPTION

FIG. 1 is a front perspective view of our machine tool display panel.

FIG. 2 is a front view thereof.

FIG. 3 is a back view thereof.

FIG. 4 is a left side elevational view thereof.

FIG. 5 is a right side elevational view thereof.

FIG. 6 is a top plan view thereof; and,

FIG. 7 is a bottom plan view thereof.

The broken lines illustrate environmental features that form no part of the claimed design.

1 Claim, 3 Drawing Sheets(56)
